E. L. SIBLEY

HOLLOW RIVET

Filed July 14, 1925

INVENTOR

Edward L. Sibley
by Wm. J. Turner
ATTORNEY

UNITED STATES PATENT OFFICE.

EDWARD L. SIBLEY, OF BENNINGTON, VERMONT.

HOLLOW RIVET.

Application filed July 14, 1925. Serial No. 43,573.

This invention relates to hollow rivets, especially designed for fastening papers or paper documents, of the well known "Challenge" eyelet type, which are manufactured under the patent to E. L. Sibley, No. 358,225, dated February 22, 1887, and ordinarily manufactured from a radiate blank such as shown in that patent or a radiate blank such as shown in the patent of E. L. Sibley, 2nd, No. 1,469,757, dated October 2, 1923, both of these blanks having flange-forming terminals projecting from opposite, that is to say, both edges of the radiating fingers or sections and involving some waste of material in the manufacture of the hollow rivets.

The present invention by the patentee of Patent, No. 1,469,757, above mentioned, consists of a radiate blank having four fingers or sections, the flange forming ends of which are extended laterally from one edge, preferably the right side edge, only of these fingers or sections, thereby effecting economy in production without impairing the operation or usefulness of the hollow rivet, as I will proceed now to explain and finally claim.

In the accompanying drawings, illustrating the invention, in the several figures of which like parts are similarly designated, Figure 1 is a plan view of the blank from which the hollow rivet shown in Figs. 3 and 4 is made. Fig. 2 is an edge view of the blank. Fig. 3 is a top plan view of a hollow rivet formed from the blank shown in Figs. 1 and 2. Fig. 4 is an elevation of said hollow rivet.

Obviously, all of the views are greatly exaggerated over the normal size of the hollow rivets.

Referring to Figs. 3 and 4, the "Challenge" eyelet of this invention and of the inventions of the patents referred to, comprises a closed driving head 1, a barrel 2 and a base flange 3.

The device of this invention having these parts is formed from the blank of Fig. 1, which has the four fingers or sections 4 radiating from a solid center 5, these fingers or sections having lateral projections 6 extending from one edge only, preferably the right hand side edge, and having an arcuate outer surface 7 and a straight inner surface 8. The opposite side edge or back 9 of the fin-

gers or sections is made straight from center to outer end.

The fingers or sections 4 form the barrel 2 of the device, the center 5 forms the driving head 1 of the device, and the ends of the fingers or sections having the one-edge lateral projections form the flange 3 of the device. The blank, by means of suitable tools or machinery, is drawn into the shape of the device, the flat fingers or sections being curved transversely in the arcs of circles to form the cylindrical barrel, or they may be otherwise shaped to form the desired configuration, the cylindrical barrel and the circular flange being of the usual conventional shape.

In the formation of the flange 3, the ends of the fingers or sections are bent at right angles to the main portions of the fingers or sections, and the straight inner surface 8 of the projection 6 will lie against the end of the straight back 9 of the finger or section next to it, as indicated in Fig. 3, so that the circularity and continuity of the flange are unbroken.

While the blank having four fingers or sections with the lateral terminal extensions from one edge only lends itself most readily to economical production, it is to be understood that the invention is also applicable to blanks having a greater or less number of fingers or sections.

Variations in the details of construction are permissible within the principle of the invention and the scope of the claims following.

What I claim is:—

1. A hollow rivet, having fingers provided with lateral end projections extending from one edge only and forming a flange.
2. A hollow rivet, having a barrel and a flange formed of four fingers, each of said fingers having at its outer end a lateral projection extending from one edge thereof only.
3. A hollow rivet, having a barrel and a flange formed of four fingers, each of said fingers having at its outer end a lateral projection extending from one edge thereof only and having an arcuate outer surface and a straight inner surface.
4. A hollow rivet, having a barrel and a flange formed of four fingers, each of said

5. fingers having at its outer end a projection extending from one edge thereof only and having an arcuate outer surface and a straight inner surface, the back of the fingers being straight.

5. A hollow rivet, having a barrel and a flange formed of four fingers, each of said fingers having at its outer end a projection extending from one edge thereof only and

having an arcuate outer surface and a straight inner surface, the back of the fingers being straight, the straight back fitting the straight inner surface of the end of the adjacent finger in the formation of the flange.

In testimony whereof I have hereunto set my hand this 8th day of July, A. D. 1925.

EDWARD L. SIBLEY.
